F. E. Maynard, ATTORNEY

UNITED STATES PATENT OFFICE

CHARLES E. McKEAG, OF LOS ANGELES, CALIFORNIA

CRUTCH CUSHION

Application filed October 3, 1927. Serial No. 223,795.

This invention relates to cushion means for crutches and similar paraphernalia and has for an object to provide a simple, low-cost and very comfortable cushion.

Another object is to provide a crutch cushion having an air cushion effect and therefore has little or no tendency to solidly pack or to heat uncomfortably under the arm pit.

An object is to provide a cushion which may be readily attached to new or old crutches without any special change or tacking or screwing means and to provide a cushion which will avoid undue wear of the clothing.

There are additional objects, advantages and features of construction and combination as will be made manifest in the following specification of the herewith illustrative embodiment; it being understood that modifications, variations and adaptations may be resorted to within the scope, spirit and principle of the invention as it is more directly claimed hereinafter.

Figure 1 is a side elevation of the cushion as applied.

Figure 2 is a cross-section of the applied cushion.

Figure 3 is a detail section showing an end closure for renewal of a cushion sack.

Figure 4 is a bottom plan of the detached cushion.

The improved cushion device comprises a bottom, attaching saddle 2 having pliant side flaps 3 with marginal means for fastening close in against the top shoulder rest R of a crutch C.

In the present case the fastening means includes a lacing string S rove in opposite flap eyelets 4. The flaps have end portions to draw around in front of the crutch bars to prevent end shift of the saddle when laced on.

Extending longitudinally of, and stitched at 5 on, the saddle is a pad top 6, of pliant material, which has its ends brought around and secured to the near ends of the saddle 2.

The pad part 6 is inflated or distended by suitable means to form a cushion. Preferably a distending bag 7 is removably mounted under the pad top 6 by opening the pad end 6^a at a fastening 8. The bag 7 may be air tight and inflatable, or it may be dis-

tended by a filling of commercial sponge rubber, which, by reason of its cellular structure, has great length of life and is soft and light and does not heat in the manner of animal or vegetable fiber used for filling.

The invention claimed is:

1. A cushion for a crutch pad including a saddle part having a central imperforate part to lie upon a crutch rest and having side flaps to draw down and fasten around the rest, a pad top having side walls with side margins laid along the saddle sides and secured thereto and forming a cushion chamber between the saddle and the pad top, said chamber being openable at one end, and a bag contained in the chamber and conformed thereto, and a cushioning filling distending the bag and the pad top.

2. A cushion for a crutch pad including a saddle part having a central imperforate part to lie upon a crutch rest and having side flaps to draw down and fasten around the rest, a pad top having side walls with side margins laid along the saddle sides and secured thereto and forming a cushion chamber over the imperforate saddle, and a distending cushioning filling in the chamber.

CHARLES E. McKEAG.
